TEMPERATURE COMPENSATED TANGENT

Filed June 27, 1955

FIG. I

FIG. 3

FIG. 2

FIG. 4

FIG. 5

A circular diagram representing a device. It features a large outer circle with an inner circular area. Several components are labeled with numbers: 10 is a small rectangular block in the center; 17 is located in the upper left quadrant of the inner circle; 18 is in the lower left quadrant; 19 is in the lower right quadrant; 20 is a small rectangular block in the upper right quadrant; 21 is in the upper right corner of the outer circle; 26 is at the bottom left corner of the outer circle; 27 is in the upper left corner of the outer circle; 28 is a small rectangular block in the lower right quadrant; and 30 is a small rectangular block at the bottom right corner of the outer circle. A line labeled 14 extends from the center area towards the bottom right.

TEMPERATURE COMPENSATED TANGENT

Robert Ritson Douglas, Erie, Pa., assignor to American Meter Company, Incorporated, Erie, Pa., a corporation of Delaware

Application June 27, 1955, Serial No. 518,001

7 Claims. (Cl. 73—281)

In gas meters, changes in temperature affect the gas volume and the stiffness of the diaphragms, both of which affect the registration. This invention is intended to compensate for the temperature effects by a thermostatically adjusted tangent which changes the length of the tangent arm to offset the temperature effects. By reason of the compensation, the meter registration is corrected to correspond to gas at standard temperature so the meter registration corresponds to the heat units.

In the accompanying drawing, Fig. 1 is a top plan view of a typical tangent, Fig. 2 is an end view of the tangent, Fig. 3 is a top plan view of the Fig. 1 tangent equipped with temperature compensating elements, Fig. 4 is a bottom plan view of Fig. 3, Fig. 5 is a section on line 5—5 of Fig. 3, Fig. 6 is a diagram illustrating the operation, and Fig. 7 is a section on line 7—7 of Fig. 4.

Figs. 1 and 2 show a typical tangent having a tangent arm 1 with an opening 2 for receiving a crankshaft to which the tangent arm is rigidly connected, for example, by soldering. The tangent arm has a flattened body with screw threaded edges 3. The flattened body of the tangent arm extends through a slot 4 in a cross-head 5 so that the cross-head can be moved along the tangent arm and clamped in adjusted position between nuts 6 and 7. Adjusting screws 8 and 9 threaded in opposite ends of the cross-head move the cross-head transversely with respect to the tangent arm and thereby adjust the angular relationship of a wrist pin 10 with respect to the tangent arm. The wrist pin 10 is rigid with the cross-head 5. The construction so far described is or may be of common construction. The length of the tangent arm is adjusted by the nuts 6 and 7. The timing is adjusted by the screws 8 and 9. Most tangents include both the length and timing adjustments although any particular tangent may have a substantially different appearance.

With the tangent shown in Figs. 1 and 2, the meter will register correctly for gas at standard temperature, for example, 60° F. At higher and lower ambient temperatures, the cubic feet registration of the meter will not correctly indicate the heat units of the metered gas because of the effect of the temperature upon the gas and upon the diaphragms of the meter. In order to provide the temperature compensation, there is fixed on the wrist pin 10 a bushing 11 having at its upper end a tubular projection 12 which is connected by solder 13 to the wrist pin. The solder 13 also connects the tubular projections 12 to a bracket 14. Beneath the bracket 14 is a washer 15 which rests on a shoulder 16 on the bushing. Below the washer 15 is a crank arm 17 which rests on a shoulder 18. While the bushing 11 and plate 14 are rigidly fixed to the wrist pin 10, the crank arm 17 is freely pivoted on the bushing which serves as a pivot for the crank arm 17 and, accordingly, the crank arm 17 can freely pivot relative to the wrist pin 10.

As shown more clearly in Figs. 4 and 7, the crank arm 17 is pivoted by means of a riveted connection 19 to one end of a link 19. At the other end, the link 19 has fixed thereto a wrist pin 20 which slides in a guide way or

2

slot 21 in the bracket 14 extending along a center line connecting the crankshaft and the wrist pin 10. The rivet 18 has a spool-shaped head 21a with end flanges 22 and 23 embracing upper and lower surfaces of an arcuate portion 24 on the plate 14. The arcuate portion 24 is centered on the wrist pin 10 and the flanges 22 and 23 provide a support for the crank arm 17 and link 19. The plate 14 has a stop 25 which engages the rivet 18 and limits the movement of the crank arm 17 in a counter-clockwise direction as viewed in Fig. 3 (clockwise as viewed in Fig. 4). When the stop 25 comes into play, the rivet 18, the wrist pin 10, and the wrist pin 20 are substantially on the same center line. This is the low temperature position of the tangent. In this position, the wrist pin 20 is closest to the crankshaft and the measuring stroke of the gas meter diaphragm is shortest. Accordingly, each stroke of the diaphragm measures a smaller quantity of gas which is appropriate when the gas is at a very low temperature and has its maximum density.

The temperature control of the position of the wrist pin 20 is effected by a coil-shaped thermostat 26 having one end 27 rigidly fixed to a flange 28 on the crank arm 17 and having its other end anchored to a member 30 slidable in a slit 31 in the plate 14. The purpose of the slidable member 30 and the slot 31 is to fix the end 32 of the thermostat 26 in a fixed angular relation with respect to the wrist pin 10 but to permit radial movement in the slot so that the thermostat will not have restraints. In other words, the thermostat 26 is free to assume its normal position.

Under the expansion and contraction resulting from changes in temperature, the end 27 of the thermostat 26 pivots the crank arm 17 about the wrist pin 10 as a center. This causes a gradually increasing movement of the wrist pin 20 in the slot 21 as the crank arm 17 turns clockwise about the wrist pin 10 as viewed in Fig. 3. This action is more clearly evident from Fig. 6 which is a greatly simplified drawing. The motion of the wrist pin 20 can very accurately compensate for the temperature effects in the meter so that the meter registration will accurately reflect the heat units in the gas instead of the cubic feet.

This temperature compensating construction can be applied to any tangent. It will be noted from Fig. 3 that the angular adjustment screws 8 and 9 are readily accessible from the top and that clearance openings 33 and 34 in the plate 14 provide access to the stroke or length adjustment nuts 6 and 7. Accordingly, all of the usual adjustments for gas meters tangents can be made on a standard tangent. The parts for effecting the temperature compensation, namely, the bushing 11, the support 14, the crank arm 17, the link 19 and the thermostatic element 26 comprise a separate assembly which can be mounted on the wrist pin of any conventional tangent. When so mounted, the wrist pin 20 of the thermostatically controlled assembly becomes the wrist pin of the tangent and yet the movement of the thermostatically controlled wrist pin 20 does not affect the construction and calibrating adjustments of the conventional tangent such as that disclosed in Figs. 1 and 2. Accordingly, the calibrating adjustments can be made on the conventional tangent and the elements providing the temperature compensation then provide the additional temperature compensation without interfering with the calibrating adjustments.

Although the wrist pin 20 is thermostatically moved, the reciprocating forces incident to the operation of the meter cause substantially no changes in the position of the tangent. The reciprocating forces are transmitted from the wrist pin 20 through the link 19 and are largely taken by the crank arm 17 rather than by the thermostat 26.

The wrist pin 20, accordingly, is not substantially moved by the reciprocatory forces incident to the operation of the meter. Furthermore, increasing valve friction makes a meter displace more gas volume than recorded and increases the torque on the wrist pin 20 in a direction which partially compensates the greater displacement.

What is claimed as new is:

1. In a gas meter tangent, a tangent arm for connection to a crankshaft, a pivot on the tangent arm spaced from the crankshaft, means on the tangent arm for adjusting the pivot with respect to the tangent arm toward and away from the crankshaft, a bracket fixed to the pivot, said bracket having a guide way therein extending along a center line connecting the crankshaft and pivot, a crank arm pivoted on the pivot, a wrist pin slidable in the guide way, a link connecting the crank arm and wrist pin, and a thermostatic element responsive to gas temperature connected between the bracket and crank arm for pivoting the crank arm in accordance with the gas temperature.

2. In a gas meter tangent having a tangent arm for connection to a crankshaft, a wrist pin on the tangent arm and spaced from the crankshaft, and means on the tangent arm for adjusting the relative distance between the wrist pin and crankshaft, the combination of temperature compensating mechanism having a bracket fixed to the wrist pin, said bracket having a guide way therein extending along a center line connecting the crankshaft and wrist pin, a crank arm pivoted on the wrist pin, a second wrist pin for connection to the meter measuring mechanism slidable in the guide way, a link connecting the crank arm and the second wrist pin, and a thermostatic element responsive to gas temperature connected between the bracket and crank arm for pivoting the crank arm in accordance with the gas temperature.

3. In a gas meter tangent having a tangent arm for connection to a crankshaft, a wrist pin on the tangent arm and spaced from the crankshaft, and means on the tangent arm for adjustably moving the wrist pin toward and away from the crankshaft, the combination of a bushing fixed to the wrist pin, a bracket fixed to the bushing, said bracket having a guide way therein extending along a center line connecting the crankshaft and wrist pin, a crank arm pivoted on the bushing, a second wrist pin slidable in the guide way, a link connecting the crank arm and the second wrist pin, and a thermostatic element responsive to gas temperature connected between the bracket and crank arm for pivoting the crank arm in accordance with the gas temperature.

4. In a gas meter tangent, a bracket for connection to a crankshaft, a wrist pin movably mounted on said

bracket, a crank arm having one end pivoted on the bracket, a link connected between the other end of the crank arm and the wrist pin, and a thermostat responsive to gas temperature mounted on the bracket and connected to the crank arm for turning the crank arm, said bracket having a guide way for the wrist pin extending along a center line connecting the crankshaft and wrist pin.

5. In a gas meter tangent, a support for connection to a crankshaft, a wrist pin movably mounted on said support, a linkage comprising a crank arm and link connected to each other by a common pivot, the crank arm having an end extending from the common pivot and pivoted on the support, the link extending from the common pivot and having an end connected to the wrist pin, a thermostat responsive to gas temperature mounted on the support and connected to the linkage for turning the crank arm, said support having guide means for the wrist pin extending along a center line connecting the crankshaft and wrist pin.

10 6. In a gas meter tangent, a support for connection to a crankshaft, a wrist pin movably mounted on the support, a crank arm having one end pivoted on the support, a link connected between the other end of the crank arm and wrist pin, means for adjustably moving the end of the crank arm pivoted on the support toward and away from the crankshaft, a thermostat responsive to gas temperature and connected between the crank arm and support for turning the crank arm, and said support having a 15 guide way for the wrist pin extending along a center line connecting the crankshaft and wrist pin.

25 7. In a gas meter tangent, a bracket for connection to a crankshaft, a wrist pin movably mounted on the bracket for movement toward and away from the crankshaft, a crank arm having one end pivoted on the bracket, a link 20 connected between the other end of the crank arm and the wrist pin, a thermostatic element responsive to the gas temperature coiled about the crankshaft and having opposite ends respectively connected to the bracket and to the crank arm for turning the crank arm, at least one 25 of the connections to the thermostatic element including a pin and slot connection with the slot transverse to the associated end of the thermostatic element, and said bracket having a guide way for the wrist pin extending along a center line connecting the crankshaft and wrist pin.
